US0D1015655S

(12) **United States Design Patent** (10) Patent No.: **US D1,015,655 S**
(45) Date of Patent: ** Feb. 20, 2024

(54) **SPRAY ARM FOR A DISH TREATING APPLIANCE**

(71) Applicant: **WHIRLPOOL CORPORATION**,
Benton Harbor, MI (US)

(72) Inventors: **Jonathan D. Pugh**, Benton Harbor, MI
(US); **Ameresh B. Viswanathan**, Saint
Joseph, MI (US)

(73) Assignee: **Whirlpool Corporation**, Benton
Harbor, MI (US)

(**) Term: **15 Years**

(21) Appl. No.: **29/841,401**

(22) Filed: **Jun. 6, 2022**

Related U.S. Application Data

(62) Division of application No. 29/714,825, filed on Nov.
26, 2019, now Pat. No. Des. 956,372.

(57) **CLAIM**

The ornamental design for a spray arm for a dish treating appliance, as shown and described.

DESCRIPTION

FIG. 1 is a top, front perspective view of a spray arm for a dish treating appliance according to our design;

FIG. 2 is a top view of the spray arm of FIG. 1;

FIG. 3 is a bottom view of the spray arm of FIG. 1;

FIG. 4 is a right side view of the spray arm of FIG. 1;

FIG. 5 is a left side view of the spray arm of FIG. 1;

FIG. 6 is a front view of the spray arm of FIG. 1; and,

FIG. 7 is a rear view of the spray arm of FIG. 1.

Portions of the drawings shown in broken lines form no part of the claimed design.

1 Claim, 3 Drawing Sheets
